IRONING BOARD COVER FASTENER

Vernon Lee Pearson, Medford, Oreg., assignor of
one-third to George H. Jackson, Medford, Oreg.

Application August 27, 1951, Serial No. 243,796

5 Claims. (Cl. 38—140)

1

This invention relates to improvements in ironing boards and more particularly to an improved means of fastening a cover on an ironing board.

An object of this invention is to provide an improved ironing board cover fastener that will permit the padding and cover for an ironing board to be readily positioned thereon in a more rapid manner than heretofore had been possible.

A further object of this invention is to provide a novel combination of ironing board and ironing board cover fastener that includes a plate for protecting the ironing board from excessive wear together with a turnbuckle, cable and hand wheel, which hand wheel is used for causing the turnbuckle to urge the cable into a groove formed in the ironing board so as to hold the ironing board cover in a secure manner.

Still further objects of the invention reside in the provision of an ironing board cover fastener that is strong, durable, highly efficient in operation, simple in construction and manufacture, capable of being readily installed on either a wooden or metal ironing board, and which is relatively inexpensive to produce.

These, together with the various ancillary objects of the invention which will become apparent as the following description proceeds, are obtained by this ironing board cover fastener, a preferred embodiment of which has been illustrated in the accompanying drawings, by way of example only, wherein:

Figure 1 is a top plan view showing the ironing board cover fastener as operatively installed on an ironing board;

Figure 2 is a vertical sectional view as taken along the plane of line 2—2 in Figure 1;

Figure 3 is a vertical sectional view as taken along the plane of line 3—3 in Figure 2;

Figure 4 is an end elevational view of the ironing board with the ironing board cover fastener operatively installed thereon;

Figure 5 is a perspective view of the ironing board used in the present invention;

Figure 6 is a perspective view of the plate comprising one element of the present invention.

With continuing reference to the accompanying drawings, wherein like reference numerals designate similar parts throughout the various views, reference numeral 10 generally designates an ironing board which is formed with a peripheral groove 12 and which additionally has a recess 14 formed in one edge together with a centrally located notch 16.

As is conventional there is positioned on the ironing board suitable padding 18 for protecting

2

the board from the heat of the iron and also to provide a suitable ironing surface that is somewhat resilient.

There is first positioned within the recess 14 the plate generally indicated at 20 which includes an upper member which is substantially U-shaped having legs 22 and 24. A lower member having legs 26 and 28 is provided. The ends of the legs 22 and 26 are connected by a central connecting portion 30 and the legs 24 and 28 are connected by a central connecting portion 32. Thus is formed an end plate of substantially U-shape in cross section. This can be readily seen as in Figure 2. Hence, the plate may be considered as having a notch 34 formed therein which is adapted to be in alignment with the notch 16 when the plate 20 is positioned with the upper member overlying the upper surface of the board and cover and the lower member underlying the under surface of the board. Positioned within the recess 14 is a turnbuckle 36 to which the ends of the cable 38 received in the groove 12 is emplaced. A suitable cover 40 is held in position by the cable 38 pressing into the groove 12. A hand wheel 42 is provided and has an opening 44 therethrough, the turnbuckle 36 being received within the opening so as to be controlled by the wheel 42 for rotation. Hence, upon rotation of the wheel 42 the turnbuckle is also rotated thus tightening or loosening the cable 38. The wheel 42 is so positioned as to be received within the notch 16 and the notch 34 between the legs 22 and 24 and 26 and 28.

Since from the foregoing the construction and advantages of this ironing board cover fastener are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be readily resorted to which fall within the scope of the appended claims.

Having described the invention, what is claimed as new is:

1. In combination with an ironing board having a groove extending around the edges thereof and having a recess with a centrally located notch in one end of said board, an ironing board cover fastener comprising an end plate having upper and lower parallel U-shaped members, each of which members have substantially par-

allel legs, the legs of said upper member being secured to the legs of said lower member by central connecting members, a cable adapted to fit in said groove in said board, a turnbuckle connecting the ends of said cable, said turnbuckle being receivable within said recess, said end plate being positioned on said board in said recess with said upper member overlying the upper surface of the board and the lower member underlying the lower surface of the board, a hand wheel, said hand wheel having an opening therethrough, said turnbuckle extending through said opening and being controlled for rotation by said hand wheel, said hand wheel being positioned so as to extend between said legs and in said notch.

2. In combination with an ironing board having a groove extending around the edges thereof and having a recess and a centrally located notch in one end thereof, an ironing board cover fastener comprising an end plate of substantially U-shape in cross section and having an upper member adapted to overlie the upper surface of said board and a lower member adapted to overlie the lower surface of said board, a central connecting portion connecting said upper member and said lower member, a notch in said plate forming legs in said upper member and said lower member, said plate being positioned with said notch in said plate in alignment with the notch in said board, a cable adapted to fit in said groove in said board, a turnbuckle connecting the ends of said cable, said turnbuckle being received within said recess, a hand wheel having an opening therethrough, said turnbuckle extending through said opening and being controlled for rotation by said hand wheel, said hand wheel being positioned in said notch in said board and said notch in said plate and between said legs.

3. The combination of claim 2 wherein said opening in the hand wheel is in the form of an

elongated slot, said slot permitting movement of said hand wheel relative to said turnbuckle and into and out of engagement with said U-shaped end plate.

5 4. An ironing board cover fastener for an ironing board having a groove extending around the edge thereof, said fastener comprising a flexible member having the ends thereof connected by a turnbuckle, a hand wheel carried by said turnbuckle, a notched plate adapted to be carried by the ironing board, said hand wheel being provided with means for locking the same against rotation, said means including projections on said hand wheel engageable in the notch of the notched plate.

10 5. An ironing board cover fastener for an ironing board having a groove extending around the edge thereof, said fastener comprising a flexible member having the end thereof connected by a turnbuckle, a hand wheel carried by said turnbuckle, a notched plate adapted to be carried by the ironing board, said hand wheel being provided with means for locking the same against rotation, said means including projections on said hand wheel engageable in the notch of the notched plate, said turnbuckle fitting in a slot in said hand wheel said hand wheel being movable relative to said turnbuckle whereby said hand wheel may be selectively moved into or out of locking engagement with said notched plate.
